CLAIM

(57) The ornamental design for a combined headphone and audio player, as shown and described.

DESCRIPTION

FIG. 1 is a front elevational view of a first embodiment of a combined headphone and audio player showing our new design;

FIG. 2 is a rear elevational view thereof;

FIG. 3 is a left side elevational view thereof;

FIG. 4 is a bottom plan view thereof.

FIG. 5 is an enlarged front elevational view showing the claimed portion of the embodiment of FIG. 1;

FIG. 6 is an enlarged rear elevational view thereof;

FIG. 7 is an enlarged left side elevational view thereof; and

FIG. 8 is an enlarged bottom plan view thereof.

FIG. 9 is a front elevational view of a second embodiment of a combined headphone and audio player showing our new design;

FIG. 10 is a rear elevational view thereof;

FIG. 11 is a left side elevational view thereof; and

FIG. 12 is a bottom plan view thereof.

FIG. 13 is an enlarged front elevational view showing the claimed portion of the embodiment of FIG. 9;

FIG. 14 is an enlarged rear elevational view thereof;

FIG. 15 is an enlarged left side elevational view thereof; and, FIG. 16 is an enlarged bottom plan view thereof.

The broken lines indicate unclaimed portions and form no part of the claimed design. FIGS. 5-8 of the first embodiment and FIGS. 13-16 of the second embodiment are shown in enlarged scales for more clarity.
